AUGUST D. EITZEN, OF NEW YORK, N. Y., ASSIGNOR TO NEWS PROJECTION CORPORATION, OF NEW YORK, N. Y., A CORPORATION OF NEW YORK

TICKER PROTECTING MEANS

Application filed February 8, 1929. Serial No. 338,344.

This invention relates to stock quotation tickers in general and more especially to means for protecting the stock quotation ticker from injury from tape pulling devices which are generally used with stock quotation projecting machines.

When tape pulling devices are used for taking up the tape as it is discharged from the ticker, care must be taken that the tension exercised by the tape puller is properly controlled so that it will give sufficient tension when the printing wheel is in engagement with the tape or the ticker is at rest to throw the printing wheel or other mechanism of the ticker out of alignment. To this end, the present invention aims to provide a device for positively locking the tape from being pulled by the tape pulling device whenever the ticker is at rest.

Specifically, the present invention still further aims to provide a tape locking means which is controlled by one of the magnets of the ticker whereby the locking device is released whenever the magnet is energized during the transmission of a message, and which is permitted to lock the tape from being pulled by the tape puller whenever such magnet is de-energized during the time when the ticker is at rest.

These and other features, capabilities and advantages of the invention will appear from the subjoined detail description of one specific embodiment thereof illustrated in the accompanying drawings in which

Figure 1 is a side elevation showing the present improvement attached to a ticker, the ticker being illustrated diagrammatically;

Fig. 2 is a fragmental section on the line 2--2 of Fig. 1; and

Fig. 3 illustrates diagrammatically the combination of a ticker, projecting machine and tape pulling device.

In the embodiment shown, the ticker 1 is provided with the usual presser arm 2 which is pivoted by means of the screw 3 to the ticker housing 1 at the front end of the ticker, the rear end of the presser arm 2 being connected by the spring 4 with the abutment screw 5.

The tape T passes adjacent to the presser

arm 2 over the discharge bracket member 6 to the projecting machine 7 and then to the tape puller P. To the presser arm 2 there is secured a spring 8 having its front straight end clamped against the presser arm 2 by the plate 9 and its rear end curved downwardly to form the loop 10, having a curved finger portion 11 adapted to engage the tape T as it passes over the discharge block 6 and to press the tape T into locking engagement with the discharge block 6 when the presser arm is released and pulled downwardly by the spring 4. To the side of the presser arm 2 there is provided an armature 12 adapted to be attracted by the magnet 13, in turn to raise the presser arm 2 upwardly about its pivot point 3 when the magnet 13 is energized.

The magnet 13 forms a part of the ticker mechanism 1 and is energized whenever a message is transmitted by the ticker. When it is so energized by other mechanism not shown, the tape T is advanced as the message is recorded on the tape T. While it is being so advanced, the tape puller P is operably connected to take up the tape T as it is so discharged and pull it through the projector 7. The tape T, in the present instance, is free to be pulled by the tape puller P whenever a message is transmitted due to the fact that at such time the presser arm 2 is raised and consequently the friction finger 11 in turn also raised sufficiently to permit the tape T freely to pass over the discharge block 6.

It will also appear that since the ticker feeding action of the tape T always takes place after the printing action, and the lever 2 is only elevated by the magnet 13 during the printing action and released before the succeeding ticker feeding action, the finger 11 will have engaged the tape T during the ticker feeding action to thereby iron out the vibrations transmitted to the tape during this ticker feeding action and thus prevent the transmission of such vibrations to the portion of the tape in the projecting machine.

Furthermore, as will appear from Fig. 1, when the finger 11 impinges the tape against the abutment 6, slack is formed in the tape before the tape reaches the abutment 6, so that the vibrations transmitted to the tape by the

ticker feeding action will be taken up in such slack and dissipated by the finger 11 and abutment 6 to prevent such vibrations being transmitted to the portion of the tape located in the projector 7. Such slack also forms a reserve to permit the tape being pressed into engagement with the printing mechanism, not shown, so that the pulling action of the tape puller will then merely take up the slack during the printing action without exercising any pulling force on the printing mechanism.

It is obvious that various changes and modifications may be made to the details of construction without departing from the general spirit of the invention as set forth in the appended claims.

I claim:

1. The combination with a ticker, of a tape puller, a friction creating finger for frictionally engaging the surface of the tape when at rest, and for permitting the tape to move immediately that the frictional contact is broken, and means associated with the ticker for actuating said friction creating finger to liberate the tape when said ticker is operating.

2. The combination with a ticker, of a yieldable friction creating device for frictionally locking the tape against movement when said ticker is at rest and for permitting the tape to move immediately that the frictional contact is broken, means associated with said ticker for actuating said device to liberate the tape when a message is transmitted by said ticker, and a tape puller for pulling said tape as it is discharged by said ticker when said device is actuated to liberate the tape.

3. The combination with a ticker having a magnet, a presser arm, and a discharge block over which the tape passes as it is discharged by the ticker, of a yieldable finger connected to said presser arm and normally locking the tape by frictionally impinging the same against said discharge block when the ticker is at rest and for permitting the tape to move immediately that the frictional contact is broken, said magnet being adapted to be energized and operatively associated to actuate said presser arm to cause said yieldable finger to liberate the tape when a message is transmitted by said ticker.

4. In a ticker the combination with a magnet, of a pivotally mounted presser arm, an armature secured to said presser arm and operatively mounted to be attracted by said magnet, a discharge block, a spring finger secured to said presser arm, and a spring connected to said presser arm for yieldably causing said spring finger to lock the tape in engagement with said discharge block when said magnet is de-energized and the ticker is at rest and for permitting the tape to move immediately that the frictional contact is

broken, said magnet when energized being operative to attract said armature and thereby raise said presser arm to cause said spring finger to release the tape when a message is transmitted by the ticker.

AUGUST D. EITZEN.
